DESIGN FOR A LUMINAIRE FOR BLACKOUT LIGHTING

Thomas W. Rolph, Newark, Ohio, assignor to
Holophane Company, Inc., New York, N. Y., a
corporation of Delaware

Application September 10, 1942, Serial No. 108,173

Term of patent 14 years

To all whom it may concern:

Be it known that I, Thomas W. Rolph, a citizen of the United States of America and a resident of Newark, in the county of Licking and State of Ohio, United States of America, have invented a new, original, and ornamental Design for a Luminaire for Blackout Lighting, of which the following is a specification, reference being had to the accompanying drawing, forming a part thereof.

Figure 1 is a perspective view of the luminaire for blackout lighting showing my new design;

Figure 2 is a side elevation thereof, with parts broken away and in section; and

Figure 3 is a bottom plan view of the same.

The design is characterized by an opaque hood A, an annular light transmitting window B and an opaque central bottom portion C.

I claim:

The ornamental design for a luminaire for blackout lighting, substantially as shown and described.

THOMAS W. ROLPH.
